UNITED STATES PATENT OFFICE.

CHARLES J. WERNER, OF NEW YORK, N. Y.

FISHING-REEL.

SPECIFICATION forming part of Letters Patent No. 437,542, dated September 30, 1890.

Application filed February 5, 1890. Serial No. 339,355. (No model.)

To all whom it may concern:

Be it known that I, CHARLES J. WERNER, a citizen of the United States, residing in the city, county, and State of New York, have invented a new and useful Improvement in Fishing-Reels, of which the following is a specification.

This invention relates to the large reels used principally for salmon and other large fish, in which reels the winding-bobbin is mounted on an open frame which is attached to the fishing-pole.

The object of my invention is to conveniently provide for the self-support of such reels in an upright position when fixed on the pole and for the ready connection and disconnection of the bobbin and crank for winding up the fishing-line or letting it run, as desired, and to otherwise improve the construction of reels of this class.

The invention consists of a novel construction and combination of parts, as hereinafter claimed; and in order that the invention may be fully understood, I shall, previous to claiming the same, describe in detail the mode in which the same may be carried into effect. Reference is to be had to the accompanying drawings, forming part of this specification, in which—

Figure 1 is a side elevation of a fishing-reel embodying my invention applied to a pole, the latter being indicated in dotted lines. Fig. 2 is a cross-sectional elevation of the same. Figs. 3 and 4 are detail views illustrating parts hereinafter referred to.

Like letters of reference designate corresponding parts in the various figures.

The frame A of the reel is made of a single piece of metal of U shape, having an ordinary pole-socket B at the base of the U and split bearings C at the ends of the arms of the U for the shaft D of the bobbin E, the split ends of each bearing C being extended laterally to form lugs C', which are adjustable together by binding-screws F, so that compensation may be made for wear of the bobbin-shaft D.

On one arm of the U-frame is fixed an oval box G, having a removable cover-plate G' and inclosing the end of the bobbin-shaft 50 D, which projects through that arm and carries a fast pinion H.

A balanced handle-crank I is fixed on a short shaft J, which is mounted to turn in and slide lengthwise through the cover-plate G', 55 and its inner end, which is tubular, mounted to slide and turn on a fixed guide-pin K, projecting within the box G, said inner end of the crank-shaft carrying a fast spur-wheel L, which normally engages the pinion H and 60 causes the bobbin E to revolve much faster than the crank I.

A spring M is placed on the crank-shaft D between the cover-plate G' and spur-wheel L to hold the gears normally in engagement, 65 and a lever-like handle N, having a fork N' on its inner end, is pivotally mounted in a slot O in the wall of the box G, with its fork N' embracing the guide-pin K behind the spur-wheel L and its other end projecting 70 outward and downward at the side of the pole when attached to the reel, so that, when desirous of letting the fishing-line run, by compressing the pole and handle N together the spur-wheel L will be pressed outward and 75 separated from the pinion and the bobbin thus disconnected from the turning gear.

The handle N terminates at the plane of the bottom of the attached pole, so as to serve as a leg to hold the reel upright when placed 80 on a flat rest.

I claim as my invention—

The herein-described U-shaped reel-frame, the upper ends of the arms of which are formed integrally with split bearings C and 85 binding-lugs C', in combination with bearing adjusting-screws F, connecting each pair of lugs C', substantially as specified.

CHARLES J. WERNER.
